UNITED STATES PATENT OFFICE.

WILLIAM H. McKISSICK, OF TULSA, OKLAHOMA.

SAFETY BLOCK.

Application filed November 6, 1925. Serial No. 67,227.

This invention relates to new and useful improvements in safety blocks.

The object of the invention is to provide a block having a housing made of complementary side members arranged so that one member may be shifted or displaced laterally of the other, thus opening the cable channels on each side of the pulley to permit a free stringing or unstringing of the cable, without danger of injury to the hands of the workman.

A further object of the invention is to provide a separator at the upper end of the block and within the same, so that the workman's hands or fingers cannot be drawn in between the sheave and the cable.

Another object of the invention is to provide handles on opposite sides of the block for readily handling the same.

20 A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a block constructed in accordance with my invention,

30 Fig. 2 is an end elevation of the same,

Fig. 3 is a view similar to Fig. 1 showing the block open,

Fig. 4 is an end elevation of the same,

Fig. 5 is a transverse vertical sectional view taken on the line 5—5 of Fig. 2,

35 Fig. 6 is a transverse vertical sectional view taken on the line 6—6 of Fig. 4,

Fig. 7 is a transverse cross-sectional view taken on the line 7—7 of Fig. 1 showing the 40 housing closed, and

Fig. 8 is a transverse cross-sectional view taken on the line 8—8 of Fig. 3 showing the housing open.

In the drawings the numeral 10 designates a clevis which is pivoted to the upper ends of hanger straps or bars 11 and 12 respectively by a bolt 13 passing through the apertured ends of said parts.

The bar 11 is suitably secured along one side of a housing member 14; while the other bar 12 is suitably fastened along the outer side of the other housing member 15.

The bars may be riveted to the sides of the housing or otherwise fastened. The apertured ends of the

55 bars extend substantially an equal distance beyond the top of the block.

The housing member 14 has a lip or extension 14' projecting downward beyond the lower edge of the member 15. The bar 11 is bent to form a hook loop 16 depending from the lip; while the bill 17 of the hook extends upwardly and overlaps the lower projecting end of the bar 12. The lower end of the bar 12 is bent inwardly at substantially right angles to form a keeper 18 within the hook. The bar 12 and the bill 17 have registering apertures 19 for receiving a locking pin 20 which also penetrates the lip 14' and the bar 11. The pin has an eye connected to one end of a short chain 21 secured to a small post 22 which is riveted in the bar 12 and the member 15. This pin is secured in place by a cotter key 23 passing therethrough at the inner side of the bar 12 and attached to a chain 24.

The housing members 14 and 15 are preferably formed of flat plates, but this is subject to variation. The member 14 has in-turned guard flanges 25 along each vertical edge; while the member 15 has similar 80 guard flanges 26 along each vertical edge. The flanges 25 are directed toward the flanges 26, but clearance is left between their edges. A short axle 27 penetrates the parts 11, 14, 15 and 12 and is suitably secured in place. 85 A sleeve or pulley 28 is mounted on the axle within the housing. The axle is located eccentrically with relation to the vertical axis or center line of the housing, being in the present instance displaced to the left 90 (Figs. 1 and 3).

It will be seen that when the parts are in their normal position as is shown in Figs. 1, 2 and 7 the guard flanges 25 and 26 are aligned so that their sides are substantially 95 flush. By this structure a practical and efficient block housing is provided and the cable (not shown) is properly retained and covered by the housing. By removing the bolt 13 and the pin 20 the clevis 10 may be 100 detached from the bars 11 and 12 and the lower end of the bar 12 is freed from the bill 17 of the hook loop 16. Of course the block will have to be placed in a horizontal position as on the derrick floor or otherwise 105 supported, when the clevis is removed.

With the pin and bolt removed the block housing may now be opened by grasping one end of the bar 12 and rotating the housing member 15 with respect to the member 14. 110 The member 15 is given a half turn which brings it to the position shown in Figs. 3,

4, and 8, whereby the block is opened. Due to the eccentric or offset mounting of the member 15 on the axle it is of course displaced laterally, with relation to the member 14, when rotated. This causes the flanges 26 to be shifted to the left (Figs. 3 and 8) and thus spaced from the flanges 25, whereby longitudinal openings are provided along each side of the block so that the cable may 10 be easily and safely inserted in the block on each side of the sheave or removed therefrom. The block is closed by turning the member 15 back to the position and replacing the parts 10, 13 and 20.

15 One of the important features of the invention is a line guard at the top of the block. This guard is shown as composed of complementary yokes 29 and 30 respectively, the yoke 29 being riveted to the inner face 20 of the member 14 and the yoke 30 being riveted to the inner face of the member 15. Each yoke has its under face or edge curved concentric to the sheave 28 and in close proximity thereto; while each end of the 25 yoke is rounded. These yokes not only separate the vertical lines of the cable between the sheave and clevis but prevent the hands or fingers of the workman from being drawn in between sheave and the cable. Each yoke 30 has substantially same thickness but are spaced sufficiently to clear each other when the block is opened. When the block is opened the yoke 30 will be carried to the bottom of the block as is shown in Fig. 6.

35 A useful feature resides in U-shaped handles 31 secured to the outer face of each block member near the upper end of the housing. This provides a ready handhold for the workman and makes for safety. It 40 is to be understood that a plurality of sheaves may be mounted in the housing.

Various changes in the size and shape of the different parts, as well as modifications and alterations may be made within the 45 scope of the appended claims.

What I claim, is:

1. In a safety block, a block housing comprising two members pivoted to each other eccentrically, one of said members being rotatable with relation to the other to open the sides of the housing, and a sheave mounted in the housing.

50 2. In a safety block, a block housing comprising two members pivoted to each other eccentrically, one of said members being rotatable with relation to the other to open the sides of the housing, and a sheave mounted in the housing, and means for locking the members against rotation.

55 3. In a safety block, a housing comprising two members eccentrically pivoted together and each having inturned side guard flanges, said flanges normally being substantially in registration with each other to close the 60 housing, one of said members being rotatable with relation to the other to displace its flanges and dispose them out of registration with the flanges of the other member to open channels on each side of the housing, a sheave in the housing, and means for locking the members in their closed position.

70 4. In a safety block, a clevis, side bars depending from the clevis, complementary housing members carried by the bars, in-turned flanges at each end of the members, separator yokes at the tops of the said members, an axle passing through the members off of their vertical centers, one of said members being rotatable on the axle with relation to the other member, a sheave journaled on the axle, a hook on the lower end of one of the side bars overlapping the lower end of the other bar, and a locking pin passing through said overlapping parts.

75 5. In a safety block, a housing comprising two members each having inturned guard flanges along each side, the flanges of one member normally alined and registered with the flanges of the other member, one of said members being displaceable parallelly to the other to move the flanges out of registration and open channels along each side of the housing, a sheave in the housing, and means for locking the members in their closed position.

80 6. In a safety block, a housing comprising two side members each provided with flanges directed inwardly at substantially right-angles thereto, said flanges terminating short of the top and bottom of said side members, whereby said members have top and bottom openings between the upper and lower edges of said flanges, the flanges of one member being directed toward those of the other member, whereby the adjacent 85 edges of said flanges are in proximity to each other and said flanges constitute guards for retaining the cable lines within the housing, one of said members being rotatable with relation to the other member to displace the flanges carried thereby, whereby the complementary edges of the flanges of said rotatable member are separated from the edges of the flanges of the other member to open the guards and permit the passage 90 of cable lines between said flanges, and a sheave mounted in the housing.

95 7. In a safety sheave block, a housing comprising two upright side members, a sheave journaled wholly within the housing, said side members extending above and below the sheave, and inwardly directed guard flanges carried by the side members of the housing and extending transversely of the groove of the sheave, said flanges being located on opposite sides of the vertical axis of the block, the flanges of one housing member being contiguous to the flanges of the other housing member, the 100 contiguous edges of the flanges being close 105 110 115 120 125 130

enough to prevent the cable lines passing therebetween, one of said housing members being movable with relation to the other housing member to displace its flanges from

5 the flanges of the other housing member, whereby the contiguous edges of said flanges are separated sufficiently to form line gaps on each side of the housing wide enough to permit the passage of cable lines therethrough.

10

8. In a safety sheave block, a housing comprising two upright side members, a sheave journaled wholly within the housing, said side members extending above and be-

15 low the sheave, and inwardly directed guard flanges carried by the side members of the housing and extending transversely of the groove of the sheave, said flanges being located on opposite sides of the vertical axis

20 of the block, the flanges on one housing member being contiguous to the flanges of the other housing member, the contiguous edges of the flanges being close enough to prevent the cable lines passing therebetween,

25 one of said housing members being rotatable with relation to the other housing member to displace its flanges from the flanges of the other housing member, where-

30 by the contiguous edges of said flanges are separated sufficiently to form line gaps on each side of the housing wide enough to permit the passage of cable lines therethrough.

9. In a safety sheave block, a housing comprising two upright side members, a sheave journaled wholly within the housing, said side members extending above and below the sheave inwardly directed guard flanges carried by the side members of the housing and extending transversely of the

40) groove of the sheave, said flanges being located on opposite sides of the vertical axis of the block, the flanges of one housing member being contiguous to the flanges of the other housing member, the contiguous

45 edges of the flanges being close enough to prevent the cable lines passing therebetween, one of said housing members being rotatable with relation to the other housing member to displace its flanges from the flanges

50 of the other housing member, whereby the contiguous edges of said flanges are separated sufficiently to form line gaps on each side of the housing wide enough to permit the passage of cable lines therethrough, the

guard flanges terminating short of the top and bottom of the side members of the housing, and guard means closing the upper end of the housing over the sheave. 55

10. In a safety sheave block, a support, a housing carried by said support and comprising two upright side members, a sheave journaled wholly within the housing, said side members extending above and below the

the sheave on opposite sides of and above and below its pivot, the flanges of one housing member being contiguous to the flanges of the other housing member, the contiguous 70

of the outer housing member, the contiguous edges of the flanges being close enough to prevent the cable lines passing therebetween, one of said housing members being movable

with relation to the other housing member to displace its flanges from the flanges of the other housing member whereby the contiguous flanges of said housing members are rendered incapable of being joined together.

uous edges of said flanges are separated sufficiently to form line gaps on each side of the housing wide enough to permit the passage of cable lines therethrough. 80

11. In a safety sheave block, a support, a housing carried by said support and comprising two upright side members, a sheave journaled wholly within the housing, said

joined wholly within the housing, said side members extending above and below the sheave, inwardly directed guard flanges carried by the side members of the housing and extending transversely of the groove of

the sheave on opposite sides of the support, the flanges of one housing member being contiguous to the flanges of the other housing member. The housing members are secured to the support by bolts.

ing member, the contiguous edges of the flanges being close enough to prevent the cable lines passing therebetween, one of said housing members being movable with relation to the other, having a movable 95

tion to the other housing member to displace its flanges from the flanges of the other housing member whereby the contiguous edges of said flanges are separated suf-

adequate clearance between the top and bottom clevises and the housing, and the top clevises are sufficiently far apart to permit the passage of cable lines therethrough, a top clevis 100

connected to the upper end of the support and suspending it, and a bottom loop connected to the bottom of the support. 105

In testimony whereof I affix my signature.

WILLIAM H. MCKISSICK.
